Primary Examiner — W. A. Teddy Falloway

(74) *Attorney, Agent, or Firm* — NIXON & VANDERHYE P.C.

(57) **CLAIM**

The ornamental design for a scent stick holder, as shown and described.

DESCRIPTION

FIG. 1 is a front view of a scent stick;

FIG. 2 is a rear view thereof;

FIG. 3 is a left side view thereof;

FIG. 4 is a right side view thereof;

FIG. 5 is a top view thereof;

FIG. 6 is a bottom view thereof;

FIG. 7 is a perspective view thereof; and,

FIG. 8 is an environmental view thereof.

The broken lines showing scent sticks in FIG. 8 represent environmental structure. The broken lines shown in FIG. 5 illustrate portions of the scent stick holder. The broken lines form no part of the claimed design.

1 Claim, 8 Drawing Sheets
